Patented Dec. 16, 1924.

UNITED STATES PATENT OFFICE.

HARRY K. CHAN, OF HONOLULU, TERRITORY OF HAWAII.

POWER-OPERATED MAGAZINE BRUSH.

Application filed December 5, 1923. Serial No. 678,584.

To all whom it may concern:

Be it known that I, HARRY K. CHAN, a citizen of the United States, residing at Honolulu, Territory of Hawaii, have invented certain new and useful Improvements in Power-Operated Magazine Brushes, of which the following is a specification.

This invention relates generally to brushes, having more particular reference to a mechanically operated magazine brush intended more particularly for use in polishing carriages, in the use of which the brush proper is moved over the surface of the part being polished by means of a suitable power device, polishing liquid being delivered when desired upon the brush from one or more receptacles embodied in the brush.

The invention has for an object the provision of a novel brush of the above type characterized by simplicity of construction and efficiency of operation.

For further comprehension of the invention and of the objects and advantages thereof, reference will be had to the following description and accompanying drawing, and to the appended claims in which the various novel features of the invention are more particularly set forth.

Fig. 1 of the drawing is a part side view and part central longitudinal vertical sectional view of a brush constructed according to my invention.

Fig. 2 is a transverse sectional view taken on the line 2—2 of Fig. 1, the brush proper being omitted.

Fig. 3 is a fragmentary transverse sectional view taken on the line 3—3 of Fig. 1.

As here embodied my improved brush comprises a casing 10 of generally elongated rectangular form. Across this casing, a short distance from opposite sides of the centre thereof, extend two transverse partitions 11 which divide the casing into a central compartment 12, of comparatively small size, in which the brush operating mechanism is located, and the relatively large end compartments 13 which serve as receptacles for polishing liquids. These compartments 13 are provided on their upper sides with suitable filling apertures closed by screw caps 14 in which small air inlets may be formed.

Formed in the bottom walls of these compartments 13, and suitably spaced thereover, are discharge openings 18 through

which the polishing liquid, or liquids, may be discharged as desired on a power operated brush. These openings 18 are controlled by valve plates 19 which fit slidably against the underside of the casing bottom and are adjustably held in guide elements 20 formed at the side edges of said casing. These valve plates 19 have formed therein the openings 22 having a like relative spacing to the openings 18 in the bottom of the casing and which are adapted to be brought into or out of registry with the said openings by moving the said plates along the guides. For adjustment purposes these plates 17 have upturned outer ends 23 on which are fixed the knobs 24. When these end elements 23 are in contact with the end walls of the casing the openings in the valve plates are out of registry with those in the liquid receptacles, as clearly shown in Fig. 1 of the drawing. By pulling the valve plates outwardly the two sets of openings are brought into registry, the outward movement of the valve plates being here shown as limited, when the said openings are in registry, by means of pins 26 on the inner ends of said plates which project upward into a longitudinal slot 27 in the bottom wall of the central compartment 12, and which are adapted to engage the ends of said slot when the said openings are in registry.

Referring now to the brush proper the latter comprises a backing element 30 of substantially equal area with the casing 10 and having fixed thereto a facing element 31. This brush is adapted to have a reciprocatory motion, longitudinally of the casing 10, imparted thereto by means of a bell crank lever 32 which is fulcrumed as at 33 in the compartment 12 and has a long arm extending downwardly through the slot 27 in the casing to engage in a socket 28 in the brush backing 30, and a short arm to which is connected one end of a rod or link 34 whose opposite end engages with an eccentric 35 on a shaft 36 in the casing. Fixed to this eccentric is a worm gear 37 with which engages a worm pinion 38 on the lower end of the shaft 39 of an electric motor 40 mounted in the compartment 12, current being supplied to this motor from a storage battery on any other suitable source of supply, through a suitable flexible lead element 41.

The brush is slidably held in position by the engagement of the backing 30 thereof

with extensions of the guides 20 for the valve plates, one of the extensions being in the form of a leaf 45 hinged as at 46 to the said guide so that it may be swung back to permit of removal of the brush. This leaf 45 may be normally held in position by means of springs (not shown) coiled in a well known manner around the pintle thereof. To conduct the liquid to the face of the brush I provide a series of tubes 48 which lead forwardly through the backing and open at their rear ends into grooves 49 in the rear face of the latter, which grooves are spaced according to the transverse spacing 15 of the apertures 18 and 22 so as to register therewith.

It is believed that the manner of operation of my improved brush will be readily understood from the above description, it 20 being readily apparent that when the motor is running a reciprocatory movement will be applied to the brush, while the liquid may be fed thereto as desired from the receptacles 13.

Having thus described my invention what I claim as new and desire to protect by Letters Patent of the United States is as follows:

1. A fountain brush comprising a casing

divided into a central compartment and end compartments, the central compartment forming a mechanism chamber, and the end compartments forming liquid receptacles, 30 guide elements on the face of said casing, under said end compartments, a brush engaged with said guide elements, means in said chamber for reciprocating said brush, and apertured valve plates interposed between the bottoms of said receptacles and the said brush.

2. A fountain brush comprising a casing divided into a central compartment and end compartments, the central compartment forming a mechanism chamber, and the end compartments forming liquid receptacles, 35 guide elements on the face of said casing, under said end compartments, a brush engaged with said guide elements, means in said chamber for reciprocating said brush, and apertured valve plates interposed between the bottoms of said receptacles and the said brush, 40 one of said guide elements being in the form of a hinged leaf adapted to be swung back for removal of the said brush.

In testimony whereof I have affixed my signature.

HARRY K. CHAN.
